Dimitar Petroff, New York, N. Y.

Application August 23, 1954, Serial No. 31,975

Term of patent 3½ years

(Cl. D3—26)

To all whom it may concern:

Be it known that I, Dimitar Petroff, a citizen of the United States, residing at New York, in the county of New York and State of New York, have invented a new, original, and ornamental Design for a Two Piece Dress, of which the following is a specification, reference being had to the accompanying drawing, forming part thereof.

In the drawing:

Fig. 1 is front elevational view of a two piece dress, showing my new design;

Fig. 2 is an enlarged, exploded view of Fig. 1; and

Fig. 3 is an enlarged, exploded rear view of the two piece dress.

I claim:

The ornamental design for a two piece dress, as shown.
